Filed Aug. 16, 1950, Ser. No. 179,841

7 Claims. (Cl. 250—17)

(Granted under Title 35, U.S. Code (1952), sec. 266)

This invention relates generally to composite tuned circuits, ultra-high frequency loop antennae, and the method of their manufacture.

In the construction of resonant loops it has heretofore been customary to resort to a circuit having the form of a closed loop made up of a plurality of metal arcuate sectors between which are mounted strips of insulating material. The proper assembly of these component parts required additional mounting elements which added to the manufacturing difficulties of producing an antenna having the required electrical and mechanical stability.

The present invention avoids these difficulties since it comprises a unitary structure which simplifies the method of manufacture, thereby facilitating greater accuracy and ease in producing a tuned circuit having a predetermined resonant frequency.

It is an object of this invention to provide a tuned circuit and loop antenna having a high resonant frequency.

It is another object of this invention to provide a new type of one-piece, composite tuned circuit for use at ultra-high frequencies.

It is a further object of this invention to provide a resonant circuit of unitary structure having high thermal and mechanical stability.

Another object of this invention is to provide a unitary structure wherein a plurality of resonant circuits are provided having capacitive and inductive coupling therebetween.

It is an object of this invention to construct a resonant circuit of the character described by a new and improved method.

A further object of this invention is to provide a method of construction of a unitary resonant circuit wherein the conductive portions of the circuit form a coating on the dielectric supporting member.

Another object is to provide a resonant circuit and loop antenna of the character described which will be simple and economical to manufacture with a high degree of reproducibility.

Other objects and many of the attendant advantages of this invention will be readily appreciated as the same becomes better understood by reference to the following detailed description when considered in connection with the accompanying drawings wherein:

FIG. 1 is a diagrammatic view of an oscillatory circuit constructed in accordance with the preferred embodiment of the invention and illustrating the composite tuned circuit;

FIG. 2 is a cross sectional view of the composite tuned antenna taken on line 2—2 in FIG. 1;

FIG. 3 is a diagrammatic view of another oscillatory circuit including two coupled resonant circuits on a common dielectric supporting member, the resonant circuits and dielectric supporting member comprising a composite tuned circuit constructed in accordance with an alternative form of the present invention; and

FIG. 4 is a sectional view of the alternative form of the composite tuned circuit taken on the line 4—4 of FIG. 3.

Referring to the drawing for a more complete understanding of the present invention and more particularly to FIGS. 1 and 2, the structure of the composite tuned circuit disclosed therein comprises a dielectric base member 5 on which is placed a covering 6 of electrically conductive material. The ring 5 may be made of any suitable

dielectric material such, for example, as ceramic, plastic, or quartz; and the ring-surface 6 may be made of any suitable electrically conductive material such, for example, as copper or silver. In this specification the term "ring" is used to designate a closed loop solid having either arcuate or straight-line bounds or both. The term "ring-surface" designates the conductive layer on a closed loop solid.

To insure proper placement of the covering 6 on the base member 5 the conducting material may be applied in any suitable manner such, for example, as by chemical deposition, electro-chemical deposition, painting, or spraying. Over a film so applied, subsequent coats may be applied by electroplating. In the case of vitreous materials the base member and covering may then be fired to obtain good adherence.

In the structure shown in FIG. 1 and FIG. 2 the inductance of the resonant circuit is constituted by the separate segments 7 of the covering 6 and the capacitance is constituted by the gaps 8 adjacent thereto. Obviously high values of capacitance can be obtained by using a ring material of high dielectric constant. The gaps 8 are formed in said covering 6 to provide a plurality of the aforementioned inductive segments 7 by masking the base member 5 before the covering is placed thereon or by removing sections of the covering after completely coating the base member. The width of the gaps or slits is usually small in comparison with the cross-sectional dimensions of the base member.

The resonant frequency of a tuned circuit constructed in accordance with the instant invention may be adjusted to any desired value over a wide range by varying the shape, dimensions or the material used for the base member 6, and to a lesser extent by varying the width of the gaps 8. By varying the number of gaps, the capacitance can be changed while maintaining the inductance substantially constant, thereby providing another means of controlling the resonant frequency.

The tuned circuit of the present invention can be used in any of the conventional circuits where resonance is desired. Impedance matching can be effected by varying the position of the gaps and the position of the connecting leads where they connect to the segments, and D.C. connections can usually be made at a neutral point near the mid-point of a given segment all of which are techniques in analogous circuits well known to those skilled in the art.

Referring to FIG. 1, a mode of utilizing the resonant circuit of the invention in an oscillator is shown. Electron discharge device 9 is operated as a conventional oscillator by connecting the high impedance of the resonant circuit between the grid 11 and plate 12. For this purpose connection can be made from these electrodes to adjacent sectors 7 of the resonant circuit, substantially as illustrated.

55 In FIGS. 3 and 4 is shown a view of the present invention wherein two coupled resonant circuits have been coated on a common dielectric supporting member 5. As hereinbefore disclosed the resonant circuits are formed by a plurality of segments 7 separated by gaps 8. Two separate tuned circuits are obtained by providing annular slots 15 in covering 6 on opposite faces respectively of segments 7. The two resonant circuits when so constructed are concentric with respect to the center of the annular supporting dielectric member 5. When so constructed the circuit can be used in any conventional manner as coupled circuits such as, for example, the push pull tuned plate tuned grid arrangement shown in FIG. 3. This circuit is arranged in a conventional manner with the plates 16 connected to one resonant circuit by leads attached to adjacent sectors 7 thereof while the grids 17 are transposed so that the grid of each of the tubes is connected to the sector of the other tuned circuit corresponding and ad-

jacent to the plate connected sector of the other of the tubes.

Obviously many modifications and variations of the present invention are possible in the light of the above teachings. It is therefore to be understood that within the scope of the appended claims the invention may be practiced otherwise than as specifically described.

The invention described herein may be manufactured and used by or for the Government of the United States of America for governmental purposes without the payment of any royalties thereon or therefor.

What is claimed as new and desired to be secured by Letters Patent of the United States is:

1. A composite tuned circuit and loop antenna for high frequencies comprising, a closed ring of dielectric material having a rectangular cross section, and a surface of conductive material contiguously surrounding substantially the entire surface of said ring and having at least one gap therein whose dimension thereacross is small compared to the lesser of the two dimensions forming the cross-sectional area of said ring, said conductive material constituting the inductance of the circuit, and the adjacent lengths of said material forming the gap constituting the structural arrangement of the capacitance of the circuit.

2. A composite tuned circuit and loop antenna for high frequencies, comprising a dielectric mass formed in a closed loop, a plurality of lengths of electrically conductive material mounted in spaced relation with respect to each other on substantially the entire peripheral surface of said mass, said conductive material constituting the inductance of said circuit, and the adjacent lengths of said material constituting therebetween the structural arrangement of the capacitance of said circuit.

3. A composite tuned circuit and loop antenna for high frequencies, comprising a unitary ring of dielectric material, an electrically conductive material thinly coated on substantially the entire peripheral surface of said ring and having gaps in said material spaced at intervals around the ring to form separate conducting portions, said portions and said gaps therebetween constituting the inductance and the capacitance of the circuit.

4. A composite tuned circuit and loop antenna for high frequencies, comprising an electrically nonconducting closed ring, a plurality of isolated electrically conducting segments of metallic film adhering to substantially the entire peripheral surface of said ring and so disposed in spaced relation thereon as to form gaps therebetween, said conducting segments constituting the inductance of the circuit, and said adjacent lengths of said conducting segments forming gaps therebetween constituting the structural arrangement of the capacitance of the circuit.

5. A multiple resonant network assembly comprising a closed ring of dielectric material, an electrically conduc-

tive material coated on substantially the entire peripheral surface of said ring, a plurality of spaced transverse gaps in said material to form separate conducting portions, said portions and said gaps therebetween constituting the inductance and the capacitance of one resonant network, and a plurality of mutually spaced annular slots in said material to form a multiplicity of individual concentric resonant networks.

6. In an oscillator network circuit comprising an oscillator, an antenna and tuned circuit including a closed ring of dielectric material, a thin coating of electrical conductive material on substantially the entire surface of said dielectric, a plurality of mutually spaced transverse gaps in said conductive material to separate conducting portions thereof, said electrically conductive material constituting the inductance of said circuit, and the adjacent lengths of said material forming said gaps constituting the structural arrangement of the capacitance of said circuit, and circuit means for interconnecting said oscillator, said antenna and tuned circuit.

7. A multiple resonant network circuit assembly comprising a closed loop of dielectric material, a plurality of lengths of electrically conductive material contiguously mounted in spaced relation with respect to each other on substantially the entire peripheral surface of said loop of dielectric material, said electrically conductive material constituting the inductance of said circuit, and the adjacent lengths of said material therebetween constituting the structural arrangement of the capacitance of said circuit, and a plurality of mutually spaced annular slots in said conductive material to form concentric resonant networks on the inner and outer radii surfaces of the said dielectric loop.
